UNITED STATES PATENT OFFICE.

JAMES FRANCIS O'ROURKE, OF TUCUMCARI, NEW MEXICO.

CEMENT RAIL FOR HIGHWAYS AND ROADS.

1,288,664.

Specification of Letters Patent. Patented Dec. 24, 1918.

Application filed June 12, 1918. Serial No. 239,583.

To all whom it may concern:

Be it known that I, JAMES FRANCIS O'ROURKE, a citizen of the United States, and a resident of Tucumcari, in the county 5 of Quay and State of New Mexico, have invented certain new and useful Improvements in Cement Rails for Highways and Roads, of which the following is a specification.

10 My present invention relates generally to roads and highways for vehicular traffic, and particularly to certain safety road making means in the form of spaced parallel rails formed of plastic material which may 15 be molded *in situ*, if desired, or laid in sections.

In the accompanying drawings illustrating my present invention,

20 Figure 1 is a perspective view illustrating the roadway formed in accordance with my invention, and

Fig. 2 is a vertical transverse section taken therethrough.

Referring now to these figures, my invention 25 contemplates the formation of a roadway which includes central and side tracks 10 and 11, each of the side tracks 11 being identical in form, and the several tracks extending longitudinally in parallelism in 30 order to form continuous supports for vehicles in passage over the highway or road and is properly spaced position for safely passing one another. To this end, the central track 10, is of considerable width and 35 has plane surfaces, its upper surface being flush with the roadway surface 12 as par-

ticularly seen in Fig. 2, and being curved if desired, to conform to the crown thereof.

The two side tracks 11, identical in construction as before described, are each of 40 trough shape and are each provided with a longitudinal groove or depression 13 to receive vehicle wheels therein, in order to maintain the same in the safely spaced relation as shown in dotted lines in Fig. 2, when 45 passing one another in either the same or opposite directions, the outer wheels of the vehicles moving in the grooves or depressions 13 of the two side tracks 11 with the inner wheels thereof upon the side portions 50 of the central track 10.

Thus by means of my invention I am enabled to quickly and economically construct vehicle roads and highways, promote safety in travel of vehicles thereover, and provide 55 for economical upkeep.

I claim:

1. A roadway having spaced parallel side tracks and a central track of which the central track has a plane surface and the side 60 tracks have longitudinal wheel-receiving depressions for the purpose described.

2. A roadway having spaced parallel tracks formed of plastic material and including track members at its center and 65 sides, the central track member being of greater width than the side track members and having a plane surface, and the side track members having longitudinal wheel-receiving depressions for the purpose de- 70 scribed.

JAMES FRANCIS O'ROURKE.
